UNITED STATES PATENT OFFICE.

GEORGE H. JOHNSTON, OF APOLLO, PENNSYLVANIA.

VALVE FOR GAS-ENGINES.

1,124,911.

Specification of Letters Patent.

Patented Jan. 12, 1915.

Application filed May 29, 1913. Serial No. 770,703.

To all whom it may concern:

Be it known that I, GEORGE H. JOHNSTON, citizen of the United States, residing at Apollo, in the county of Armstrong and 5 State of Pennsylvania, have invented certain new and useful Improvements in Valves for Gas-Engines, of which the following is a specification.

My invention relates to new and useful 10 improvements in mixing valves or carbureters for internal combustion engines and the object of my invention is to provide a carbureter which may be employed with either gaseous or liquid fuel.

15 A further object of my invention is to provide a carbureter in which the various air and fuel adjustments are simple and in which the admission of air and fuel does not in any way depend upon the action of 20 springs which readily get out of adjustment.

With these and other objects in view, my 25 invention will be more fully described, illustrated in the accompanying drawing, and then specifically pointed out in the 30 claim which is attached to and forms a part of this application.

In the drawing: Figure 1 is a perspective view of my improved carbureter; Fig. 2 is a top plan view; Fig. 3 is a central vertical 35 sectional view; Fig. 4 is an inverted perspective view of the puppet valve employed to control the supply of fuel to the carbureter.

Corresponding and like parts are referred 40 to in the following description and indicated in all the views of the drawing by the same reference characters.

The preferred embodiment of my invention, as illustrated in the drawing, consists 45 primarily of a hollow cylindrical body portion 10 provided adjacent its upper end with a laterally directed, internally threaded branch or nipple 11 adapted to receive one end of the manifold leading from the 50 carbureter to the engine cylinder or cylinders. A spider 12 is formed integrally with the lower end of this casing and a fuel supply tube 13 extends upwardly centrally through the spider, its lower end extending 55 a slight distance below the lower end of the body 10 to form a bearing for a disk valve 14 for which the spider 12 forms a seat, the radial arms of the spider and of the disk 60 valve being so proportioned as to permit

substantially a half opening of the lower 55 end of the carbureter body. The disk valve is fitted about the lower end of the tube 13 and is provided at one side with a radially extended, circumferentially slotted ear 15 through which is passed a screw 16, the 60 upper end of which is threaded into a lug 17 cast integrally with the body 10. This screw serves to hold the valve in engagement against its valve seat and also to limit the 65 turning movement thereof and in order to prevent loosening of the valve through repeated adjustment of the same, a spring washer 18 is inserted between the head of the screw and the ear 15. The disk valve is further provided with a radially extending 70 arm 19 by means of which the valve may be rotated and this arm is provided with an upwardly directed pin 20 arranged to move over a scale 21 inscribed upon the body 10 and from which the extent to which the 75 valve is opened may be readily determined.

The upper end of the body 10 is closed by a cap 22 having a centrally formed boss 23 which seats closely in the upper end of the body, the cap being secured in place by one 80 or more set screws 24 passed through the body 10 and engaging the peripheral face of the boss portion of the cap, as clearly shown in Fig. 3. The cap is provided centrally with a threaded bore, the threads 25 of 85 which are of relatively great pitch and the upper portion of an adjustable stop 26 is threaded for engagement with the threads of this bore. It will therefore be apparent that even a partial rotation of the stop will 90 considerably raise or lower the same. The lower end of the stop terminates in a head or valve stop proper 27, the lower face of which is checkered as at 28 and said valve stop limits the upward movement of a 95 puppet valve 29 which is seated over the upper end of the tube 13 and held against displacement therefrom by a plurality of spaced legs 30 extending into the upper end of the tube. The valve engaging face of 100 the valve stop is checkered to prevent sticking of the valve to the stop and consequent long continued opening of the valve.

The outer or free end of the adjustable stop 26 is reduced to form a stud 31 adapted to receive a collar 32 which in turn, carries a radially directed arm 33 provided at its outer end with a bearing 34 for a spring

pressed pawl 35, this arm 33 and pawl 35 forming in effect a throttle lever of the carbureter. The peripheral faces of the upper portion of the body 10 of the carbureter 5 and of the adjacent portion of the cap 22 are provided with a plurality of aligned notches or teeth 36 for engagement by the pawl 35 to adjustably secure the throttle valve in position. The upper face of the cap 22 is provided with a scale 37 by which the amount of opening of the throttle valve 10 may be readily determined.

The above described carbureter may be employed with either liquid or gaseous fuel 15 and its operation will be readily understood from an inspection of the drawing, it being apparent that the fuel will be drawn through the tube 13 by the suction of air through the body of the carbureter to raise 20 the valve 29 as far as permitted by the throttle lever adjustment. The fuel and air so admitted will be mixed in the upper part of the carbureter body or mixing chamber and passed from there through the branch 11 25 and intake manifold to the cylinder.

Having thus described the invention, what is claimed as new is:

In a carbureter, a body open at its lower end and providing a mixing and carbureting chamber, a spider partially closing the open 20 end of the body member and provided with a central opening, a fuel supply pipe extending through the spider, a lug formed exteriorly of the body member at its open end, a disk valve mounted for turning movement about the supply pipe and seating against the lower face of the spider, said valve being free of connection to the supply pipe, a slotted extension formed on the disk valve, and a screw passed through the 35 slot of the extension and into the lug to secure the disk valve against disengagement and permit it to have a limited turning movement.

In testimony whereof I affix my signature 40 in presence of two witnesses.

GEORGE H. JOHNSTON. [L. S.]
